HEMSTITCHING ATTACHMENT FOR
SEWING MACHINES

George L. Hinman, New Haven, and Clifford J. Word, Milford, Conn., assignors to The Greist Manufacturing Company, New Haven, Conn., a corporation of Connecticut

Application December 26, 1934, Serial No. 759,146

34 Claims. (Cl. 112—160)

This invention relates to devices for doing hemstitching work and particularly to an attachment for this purpose for the ordinary household sewing machine, and involves a number of improvements 5 on the hemstitching attachment shown in the patent of Greist and Hinman, No. 1,986,056, granted January 1, 1935.

While devices have been proposed heretofore which are designed for attachment to the usual 10 household sewing machine, in order to perform hemstitching operations thereupon, these devices in some respects are of complicated construction and for that reason are more or less expensive to manufacture and difficult to maintain in proper 15 working order.

The present invention has for one of its objects the simplification and improvement of the hemstitching attachment shown in the patent above identified in order to render such attachment 20 more accurate and positive in operation in some respects and to make cheaper its construction and the assembly of the parts thereof.

Another object of the invention is the provision 25 of a hemstitching device which will be relatively cheap to manufacture and assemble, and at the same time be efficient and positive in operation.

Another object of the invention is to provide a 30 hemstitching attachment for household sewing machines in which the length of the feed step may be varied and readily reset to its original position.

Still another object of the invention is the provision of a hemstitching attachment for household sewing machines in which the piercer may be 35 moved to inoperative position and thereafter returned precisely to its original position.

A still further object of our invention is to provide a hemstitching attachment for household sewing machines of improved design, construction 40 and operation.

To these and other ends, the invention consists in the novel features and combinations of parts to be hereinafter described and claimed.

In the drawings:

Fig. 1 is a side elevational view of our device as applied to an ordinary household sewing machine;

Fig. 2 is a top plan view of the attachment;

Fig. 3 is a side elevational view taken from the side opposite that shown in Fig. 1;

Fig. 4 is a sectional view on line 4—4 of Fig. 3;

Fig. 5 is a sectional view on line 5—5 of Fig. 2;

Fig. 6 is a detail view showing the feed operating mechanism;

Fig. 7 is an enlarged side elevational view of the attachment alone;

Fig. 8 is a sectional view on line 8—8 of Fig. 7;

Fig. 9 is a longitudinal sectional view through the attachment;

Fig. 10 is an enlarged detail view of the piercer and supporting mechanism therefor;

Fig. 11 is a sectional view on line 11—11 of Fig. 7;

Fig. 12 is a top plan view of the throat plate or cover;

Fig. 13 is a sectional view on line 13—13 of Fig. 12;

Fig. 14 is a detail view of the piercer;

Figs. 15 and 16 are detail views showing a modification of the mechanism for moving the piercer arm laterally;

Fig. 17 is a sectional view on line 17—17 of Fig. 4; and

Figs. 18 and 19 are respectively side and plan views of a modified form of the attachment.

To illustrate a preferred embodiment of our invention, we have shown in Fig. 1 a portion of the head 10 of a sewing machine having the usual presser bar 11 and needle bar 12, the latter carrying at its lower end the usual sewing needle 13.

In the use of the attachment herein described, the usual presser foot on a household sewing machine is removed from the presser bar 11 and the attachment secured to the presser bar in place thereof, as will be hereinafter described, the attachment being provided with a presser foot of its own. Also, the usual feeding plate or feeding dog in a household sewing machine is covered by the throat plate or cover 14 as the attachment is provided with a feeding arrangement to feed the cloth therethrough in accordance with the requirements of the hemstitching operation, which are different from those of the usual sewing operation.

The parts of the attachment are supported upon a base or support comprising a horizontal base or plate portion 15 provided with upstanding flanges 16 and 17 at the side edges thereof. The base plate is provided with a relatively large opening 18 adjacent its central portion, a small opening 19 rearwardly of the opening 18, and a slot 20 adjacent its rear edge. Adjacent the front edge, the plate 15 is extended forwardly and offset downwardly, as shown at 21, terminating in a presser foot 22 provided with an opening 23 through which moves the ordinary machine needle and piercer of the hemstitching attachment.

The parts of the attachment are supported upon a base or support comprising a horizontal base or plate portion 15 provided with upstanding flanges 16 and 17 at the side edges thereof. The base plate is provided with a relatively large opening 18 adjacent its central portion, a small opening 19 rearwardly of the opening 18, and a slot 20 adjacent its rear edge. Adjacent the front edge, the plate 15 is extended forwardly and offset downwardly, as shown at 21, terminating in a presser foot 22 provided with an opening 23 through which moves the ordinary machine needle and piercer of the hemstitching attachment.

The parts of the attachment are supported upon a base or support comprising a horizontal base or plate portion 15 provided with upstanding flanges 16 and 17 at the side edges thereof. The base plate is provided with a relatively large opening 18 adjacent its central portion, a small opening 19 rearwardly of the opening 18, and a slot 20 adjacent its rear edge. Adjacent the front edge, the plate 15 is extended forwardly and offset downwardly, as shown at 21, terminating in a presser foot 22 provided with an opening 23 through which moves the ordinary machine needle and piercer of the hemstitching attachment.

The parts of the attachment are supported upon a base or support comprising a horizontal base or plate portion 15 provided with upstanding flanges 16 and 17 at the side edges thereof. The base plate is provided with a relatively large opening 18 adjacent its central portion, a small opening 19 rearwardly of the opening 18, and a slot 20 adjacent its rear edge. Adjacent the front edge, the plate 15 is extended forwardly and offset downwardly, as shown at 21, terminating in a presser foot 22 provided with an opening 23 through which moves the ordinary machine needle and piercer of the hemstitching attachment.

The parts of the attachment are supported upon a base or support comprising a horizontal base or plate portion 15 provided with upstanding flanges 16 and 17 at the side edges thereof. The base plate is provided with a relatively large opening 18 adjacent its central portion, a small opening 19 rearwardly of the opening 18, and a slot 20 adjacent its rear edge. Adjacent the front edge, the plate 15 is extended forwardly and offset downwardly, as shown at 21, terminating in a presser foot 22 provided with an opening 23 through which moves the ordinary machine needle and piercer of the hemstitching attachment.

The parts of the attachment are supported upon a base or support comprising a horizontal base or plate portion 15 provided with upstanding flanges 16 and 17 at the side edges thereof. The base plate is provided with a relatively large opening 18 adjacent its central portion, a small opening 19 rearwardly of the opening 18, and a slot 20 adjacent its rear edge. Adjacent the front edge, the plate 15 is extended forwardly and offset downwardly, as shown at 21, terminating in a presser foot 22 provided with an opening 23 through which moves the ordinary machine needle and piercer of the hemstitching attachment.

The parts of the attachment are supported upon a base or support comprising a horizontal base or plate portion 15 provided with upstanding flanges 16 and 17 at the side edges thereof. The base plate is provided with a relatively large opening 18 adjacent its central portion, a small opening 19 rearwardly of the opening 18, and a slot 20 adjacent its rear edge. Adjacent the front edge, the plate 15 is extended forwardly and offset downwardly, as shown at 21, terminating in a presser foot 22 provided with an opening 23 through which moves the ordinary machine needle and piercer of the hemstitching attachment.

stance is, roughly, of L-shaped formation and may be described as consisting of connecting longitudinal and transverse slots, the longitudinal slot being relatively narrow, as shown at 23^a, 5 so that the metal of the presser foot at this point will extend fairly closely to the needle and piercer to furnish a substantial support to the cloth during the piercing operation.

The forward portion of the side flange 16 is extended to provide an integrally formed U-shaped member 24 designed to embrace the presser bar 11 and be secured thereto. The member 24 is, as stated, an integral part of the flange 16 and formed into the proper shape to embrace the 15 presser bar. This provides for the attaching of the attachment to the machine, the part 24 being secured to the presser bar by means of a screw passed through the opening 25 and threaded into the presser bar.

20 The flanges 16 and 17 are provided with aligned openings 27 and 28 to receive a rotatable shaft or arbor which extends through these flanges and carries some of the working parts of the device. This shaft, designated by the numeral 29, is provided with an enlarged portion 30 fitting in the opening 27 of the flange 16 to give the shaft a bearing therein. At the other end of the shaft the latter is provided with a reduced end portion upon which a cam 31 is secured by being forced 25 against the shoulder 32 by the upset end 33 of the shaft. At this end the shaft has a bearing in the opening in the flange 17. A hub member 33^a is non-rotatably keyed to the shaft by means of the tenon 33^b formed on the enlarged portion 30. This hub member is provided with stepped 30 portions 34^a and 35^a upon which are non-rotatably secured the cams 34 and 35, the cam member 34 being spaced from the adjacent shoulder of the step portion 35^a by an additional step portion 36. A further reduced portion 37 of the hub member abuts the flange 17. Upon the part 30 of this shaft is rotatably mounted a lever 42 having a pawl 43 pivoted thereon, which pawl is in engagement with a toothed wheel 44 non-rotatably 40 secured upon the end of the shaft 29. The lever 42 is thus loosely mounted between the toothed wheel 44 and the flange 16.

It will be apparent that this provides a very 50 convenient arrangement for the manufacture and assembly of these parts, shown more especially in Fig. 4. The toothed wheel 44 may be secured to the end of the shaft 29 by being pressed upon serrations 45 thereon, and the lever 42 mounted upon the enlarged portion 30 of this shaft against 55 this wheel. The cam members 34 and 35 are then secured upon the hub member 33^a. This hub member is then positioned between the flanges 16 and 17. The shaft 29, with the lever 42 and wheel 44 thereon, is slipped through the opening in the hub member and through the flange 17. The cam member 31 is mounted upon the reduced end of the shaft and the end of the shaft is then upset as at 33 to secure the parts in place.

60 An arm 47 is pivoted to the flange 17 by means of a bolt passing through an opening in the arm and an opening 49 in the flange. This arm extends forwardly, and secured to its free end is the piercer head 50 carrying the piercer 51.

70 The piercer head 50 is rotatably secured to a plate 50^a, the plate being secured to the forward end of the arm 47 by means of screws 52 at the ends of the plate which pass through slotted openings in the arm 47 so that the plate and piercer head may be adjusted to some extent

longitudinally of the arm 47. The piercer head 50 is mounted to rotate on the base 50^c around the opening receiving the screw 50^b, so that by loosening this screw the piercer head may be swung through an angle of 90° from the position shown in Fig. 7 to that shown in Fig. 10 where the piercer is in a horizontal inoperative position. This will be done when it is desired to use the device for making a fancy stitch of some character, such as applique work instead of the usual 10 hemstitching operation. When it is desired to return the piercer to its normal position—that shown in Fig. 7—the screw 50^b may be loosened and the piercer head is swung downwardly until the horizontal portion 51^a of the piercer strikes 15 the shoulder 50^d on the plate 50^a. This effectively locates the piercer in the proper vertical position for the hemstitching operation so that it may always be moved back exactly to its original position.

20 The forward end of the arm 47 and the plate 50^a are provided with recesses 53 and 54, shown more especially in Fig. 9, to permit this adjustment of the piercer to inoperative position.

A spring 55 normally urges the arm 47 upwardly in order to maintain its upper surface against the cam arms of the cam wheel 31. Adjacent the cam wheel, the upper surface of the arm is provided with notches 56 and 57 to receive these cam arms 58. It will be apparent that upon rotation of the shaft 29 by operation of the lever 42 and pawl 43, the cam wheel will be rotated in the direction of the arrow shown in Fig. 1. One of the arms 58 will be caused to enter the notch 57, and upon further rotation it will ride 35 up upon the high portion 59 between the notches 56 and 57 and depress the arm 47 to cause the piercer to enter the cloth. The depressed position of this arm is shown in Fig. 7. Further rotation of the shaft 29 will cause this arm 58 to 40 move opposite the notch 56, at which time the spring 55 will cause the arm 47 to move upwardly to withdraw the piercer from the cloth, and this upward movement will be checked by the engagement of the following arm 58 in the notch 45 57. There are four of these arms upon the cam 31, while there are twelve teeth upon the wheel 44; thus one stroke of the piercer arm will be effected for each three upward movements of the lever 42.

50 A lateral extension 47^a formed on the forward part of the arm 47 extends into the path of the needle bar 12 so that when the latter descends, the arm 47 will be moved downwardly and cause the piercer 51 to enter the cloth to preform an opening therein prior to the downward movement of the piercer effected by the cam wheel 31. It will be understood that the piercer is one step in advance of the needle so that while the latter is entering one opening, the former will be making a subsequent opening. It is therefore very important to have the step-by-step feed of the material upon which the hemstitching is being done conform exactly to the distance between the piercer and the needle.

60 The forward feeding movement of the cloth is effected by means of a feed bar 60 pivotally and slidably secured to the plate 15 adjacent one end by means of the rivet 61 secured in the body of the feed bar 60 and having its body portion 70 passing through the slot 20. This is not a true pivotal attachment, but nevertheless will permit a pivotal movement as well as a sliding movement of this bar in order that the free end may be raised and lowered to engage and disengage 75

the cloth. It will be noted that the opening 20 is enlarged at its rear end, as shown at 20^a, to permit the head of the rivet 61 to pass through the opening 20^a so as to detach the feed bar when desired. It will be understood that in ordinary movements of the bar, the rivet does not move sufficiently far in a rearward direction for the rivet head to register with this enlarged part of the opening.

10 Adjacent the intermediate portion of the bar, the metal thereof is displaced downwardly, as shown at 62, to provide a recess 63, and at its free end, at which the cloth enters, a pair of spring fingers 64 and 65 are secured to the bar, which 15 members are spaced so that the presser foot 22 is received between them. Surrounding the members 64 and 65 are bands of rubber or similar friction material 64^a and 65^a. These friction members engage the cloth when the feed 20 bar is pressed downwardly thereon, and as these fingers are resilient, the pressure exerted by them upon the cloth will always be substantially the same even though one may happen to be disposed at a slightly different level than the other. This 25 will provide for a straight-line feeding of the cloth, which would otherwise not be the case, for when one finger bears more firmly upon the cloth than the other, the latter is apt to be fed more upon one side than the other. The rubber bands 30 around the spring fingers will grip the cloth to effect a lateral feeding thereof during the hemstitching operation.

Between the rear ends of these spring fingers, the feed bar is provided with teeth or serrations 35 66 which grip the cloth and provide for the forward feeding thereof.

Upon the feed bar 60 are provided vertically disposed lugs 67 and 68 which project upwardly through the opening 18 in the plate 15 and which 40 are disposed upon opposite sides of the cam wheel 35 to be engaged by the cam surfaces thereof. These lugs may be conveniently formed by striking up portions of the feed bar 60, and are situated closely adjacent the recess 63. As 45 shown in Fig. 4, the lug 68 extends closely adjacent the pivoted arm 47 so as to engage this arm and move it laterally when the feed bar is moved laterally. Upon the other or outer side of the arm 47, a post or pin 68^a is secured to the feed 50 bar so that the arm 47 will be positively moved in both directions with the bar.

In Figs. 15 and 16, a slight modification is shown wherein the arm 47 is provided with a depending lug or finger 47^b which extends through 55 an elongated slot 47^c in the feed bar 60. This finger and slot connection may be used in place of the pin 68^a and that portion of the lug 68 adjacent the arm 47, as it will effect lateral movements of the arm with the feed bar 60 and at the 60 same time provide for longitudinal movements of the feed bar 60 relatively to the arm 47.

Secured to the feed bar 60 is an L-shaped member 69 which projects upwardly through the opening 19 of the plate 15, the arm being secured 65 to the feed bar by the rivet 70. A small lever 71 is pivoted to the member 69 by the rivet 72 so that it may be moved from the full-line position shown in Fig. 5 to the dotted-line position shown in that figure. The lower end of the 70 lever 71 is adapted to be engaged by the arm 73 of a bell crank lever pivoted at 74 to the flange 17. The other arm 75 of this lever is adapted to be engaged by the cam 34, the lever arms being provided at their ends with horizontal portions 75 to render these engagements more positive.

When the lever 71 is in the position shown in Fig. 6 and in the full lines of Fig. 5, the arm 73 strikes against the lower end of this lever and moves the feed bar 60 rearwardly, the rivet or pin 61 sliding through the slot 20. When the lever 71 is moved to the dotted-line position as shown in Fig. 5, the lower end thereof will no longer be in the path of the lever arm 73, but in this instance the lever arm 73 will strike against the member 69 and effect a feeding 10 movement of the bar 60, which movement, however, will be shorter than the regular movement effected through the engagement with the lever 71. This shorter movement will be used with a fancy stitch or work other than hemstitching 15 when the piercer has been moved to inoperative position. It will be apparent that when the lever is moved upwardly again to full-line position, the normal feed step will be restored, so that if the operator has shortened the feed, he may there- 20 after readily restore it to its exact original adjustment where it will properly register with the distance between the needle and piercer. A spring washer 71^a is placed under the head of the rivet to hold the lever in adjusted position. 25

The cam 35, to which reference has already been made, is provided upon its periphery with four cam surfaces 77, each of which is followed by a dwell 77^a terminating in an abrupt shoulder 78, and the material of this wheel is displaced 30 laterally at four points about its periphery, as shown at 79, to provide four lateral camming portions as well as the four vertical camming portions 77. These cams, in conjunction with the movements of the feed bar, effect the forward and side movements of the cloth. This cam wheel is substantially the same in construction and operation as that shown in the Greist and Hinman patent No. 1,986,056, above referred to. 35

At the beginning of the operation of the device, the feed bar is in the position shown in Fig. 3, which is slightly above the presser foot 22, and the shoulder 78 of the cam lies in the recess 63. When the arm 42 is brought upwardly 40 to turn the shaft 29, the cam surface 77 will depress the feed bar downwardly upon the cloth and slightly raise the presser foot therefrom, as shown, for example, in Fig. 9. Continued movement of the lever 42 will cause the lateral cam 50 portion 79 to pass between the lugs 67 and 68 and move the feed bar and cloth to the left, as shown in Fig. 8. A second stroke of the lever 42 causes the dwell 77^a of the cam wheel to hold the feed bar upon the cloth while the cam 55 portion 79 effects a return of the feed bar to the right from the position shown in Fig. 8. The needle then moves downwardly and effects another stitch in the opening made by the piercer and the parts are then in position for a forward 60 feeding of the cloth.

This forward feeding movement is accomplished by the feed bar 60, and it will be recalled that this feed bar has, by the cam portion 77 and dwell portion 77^a, been moved downwardly 65 and held against the cloth. The feeding movement of the feed bar is effected by the cam 34 and lever arm 73. This cam has four curved or dwell portions 80 which are between the high shoulder portions 81, these surfaces being in 70 position to engage against the horizontal portion of the lever arm 85, the lever arm being held against the cam by means of the spring 82 connected at one end to the lug 67 and at the other end to a stud 83 on the flange 16. This 75

- spring is inclined in an upward direction so that it not only tends to draw the lug 72 toward the cam, but also tends to draw the feed bar upwardly toward the plate 15 when it is not held down by the cams 77 and 77^a. On one side of the high point 81 on the cam 34 is an abrupt shoulder 81^a providing a depression into which the arm 75 drops to permit the feed bar to be returned to its original position by its spring.
- 10 The lever 42 is provided with a bifurcated end 89 providing a slot 90 within which is adapted to be received the usual screw attached to the needle bar 12 of the sewing machine, so that this lever is operated by the reciprocating movements of the needle bar. It will of course be understood that during the downward movements of the needle bar, the pawl 43 simply rides freely over the teeth of the wheel 44, and the upward stroke of the needle bar is the effective stroke so far as concerns the effective operation of the hemstitching attachment. It may also be observed that as there are twelve teeth upon the wheel 44, and three of these are employed during each complete cycle of operation of the hemstitching device, a complete revolution of the member 44 effects four hemstitching operations. Thus there are four cam arms 58 and four separate cam surfaces upon each of the cam wheels 34 and 35, so that each of these members performs its particular operation four times during each revolution. Each one of these cams performs one operation, therefore, during three upward strokes of the needle bar and lever 42.
- 15 30 35 The piercer 51 is shown more particularly in Fig. 14 and as there shown consists of a horizontal portion 51^a and a vertical portion 51^b. The horizontal portion is secured in an opening 51^c in the piercer head 50, as shown more particularly in Fig. 11, and is held in place by means of the setscrew 51^d, shown in Fig. 7. By loosening this screw, a lateral adjustment of the piercer may be effected.
- 40 45 50 55 The piercer itself is of a particular shape and design. Referring to Fig. 14, it will be noted that the arm 51^b is not set exactly at right angles to the portion 51^a, but instead the angle between these members is approximately 94°, so that the vertical portion of the piercer points outwardly away from the line of stitching to a slight extent. On the other hand, the point of the piercer is not tapered equally upon both sides. About one-third of the taper is provided upon what may be termed the inside, as shown at 51^e, and about two-thirds of the taper upon the opposite side, as shown at 51^f. This causes the inner edge of the piercer to lie closely against the line of stitching on its downward stroke during the second travel of the goods through the machine and provides for the goods to be pulled mainly away from the line of stitching during the stroke so that the stitching is not interfered with, and at the same time a full-sized opening will be effected. At the same time the slightly obtuse angle of the vertical portion of the piercer throws the point thereof outwardly to a sufficient extent so that the point will always clear the line of stitching and not foul or cut it during its downward movement.
- 60 65 70 75 80 As shown more especially in Fig. 5, the bell crank lever comprising the lever arms 13 and 75 is supported upon the screw 14, the shank 74^b of which is received in an opening in a collar 74^a upon the nut 74^c. The opening is slightly eccentric to the collar so that by rotating the nut

and collar, a slight adjustment of the pivotal point of the bell crank lever may be made. The nut is thereafter secured in adjusted position by tightening the screw 14. It will be seen that this arrangement provides for a slight adjustment of this bell crank lever in order to adjust the length of the feeding step accurately to the distance between the piercer and needle. This adjustment will ordinarily be made at the factory when the device is assembled and will not be changed thereafter, as any change in the length of the feeding step for different kinds of work will be accomplished through the pivoted lever 11.

5 10 15 20 25 30 35 40 45 50 55 60 65 70 75 80 85 90 95 The throat plate 14 shown in Figs. 12 and 13 is, as stated, secured to the bed of the machine below the hemstitching attachment so as to cover the usual feed dog. This throat plate is provided with a laterally elongated slot 14^a for the piercer and an opening 14^b for the needle rearwardly of this slot. It will be noted from reference to Figs. 12 and 13 that the metal of the upper surface of this throat plate is recessed forwardly and laterally about the needle opening 14^b so that the mouth of this opening lies below the horizontal level of the upper surface of the plate. The portion of the cloth in which the opening has been made by the piercer passing downwardly through the lateral opening 14^a is next fed over the needle opening 14^b. As the metal between these openings is below the surface of the plate, this metal will not form such an abrupt shoulder as would otherwise be the case, so that the "burr" which usually occurs on the lower side of the cloth due to the thrust of the piercer therethrough will not be drawn over a sharp shoulder and thus forced back into the opening to fill the same. The same action takes place when the cloth is moved laterally, as there is a lateral depression to the left of the needle opening, as shown in Fig. 12, and thus when the cloth is moved to the left, the "burr" will not be pressed upwardly into the opening.

90 95 100 A marker in the form of a line 14^c is provided on the surface of the throat plate forwardly of the piercer slot 14^a to indicate the correct setting of the point of the piercer laterally of the slot. This line may advantageously be colored black so that it will be readily distinguishable as it will then be in contrast to the polished metal surface of the throat plate. This will indicate the correct setting of the piercer with respect to the adjustment provided by the setscrew 51^d.

A brief description of the entire operation of the device may now be helpful. Assuming that a hole has been made in the cloth by the piercer and the cloth has been fed forwardly so that the needle now registers with this hole, with the parts in the position shown in Figs. 1, 2 and 3, the needle bar 12 of the sewing machine has descended to make a stitch in the cloth. During the descent of this bar the end thereof strikes the part 47^a on the piercer arm and drives the piercer into the cloth to preform another hole to be made therein. While this perforation is not essential at this time, it serves later to relieve the strain on the piercer arm when the latter in a subsequent step carries the piercer down through this same opening. When the needle bar 12 moves upwardly, the lever 42 is likewise moved upwardly and the pawl 43 moves the 70 toothed wheel 44 through a distance equal to one tooth's space, thus rotating the shaft 29. This causes one of the arms 58 (that shown in the recess 57 in Fig. 7) to ride upwardly upon the surface 59 and moves the piercer arm 47 75

- downwardly, thus moving the piercer 51 through the same hole in the cloth made, as described above, at the time of the previous descent of the needle bar and tending to increase the size of the hole. At the time that the piercer member is moving downwardly the cam surface 71 will move the feed bar 60 downwardly in contact with the cloth, thus slightly raising the presser foot 22. Thereafter, but still during the first stroke 10 of the lever 42, the lateral cam surface 79 upon the cam wheel 35 will engage the lug 68 to move the front end of the feed bar 60 from the position shown in Fig. 2 to the position shown in Fig. 7 so that the cloth will have been moved laterally to 15 the left. The piercer arm 47 is likewise moved laterally at this time by contact of the lug 68 therewith so that the piercer 51 is moved with the cloth, thus assisting in controlling the lateral movement of the cloth.
- 20 The needle bar 12 then descends to cause the needle to again enter the cloth and make a stitch to one side of the opening made by the piercer. When the needle bar again moves upwardly, a second upward stroke of the lever 42 will be produced. During this stroke the cam surface 79 moves out of contact with the lug 68, and the surface of this member contacting with the lug 67 effects a return lateral movement to the right of the free end of the feed bar 60 to bring the 30 cloth back to its original position. This lateral movement is also aided by the spring 82 which occupies a slightly diagonal position when the feed bar is moved to one side.
- 35 The needle bar again descends and makes another stitch in the opening made by the piercer, thus completing the return side stitch so as to bring the parts in position for a forward feeding movement and for a forward stitch in the cloth. When the needle bar again ascends and effects
- 40 the third upward movement of the lever 47, the cam arm 58 rides out of contact with the part 59 and drops into the recess 56, thus releasing the piercer arm 47 and permitting it to be moved upwardly out of the cloth by the spring 55.
- 45 Thereafter, the lever arm 75 is caused to ride toward the high portion 81 of the cam 34 and thus move the feed bar 60 to the right, as shown in Fig. 9, to effect a forward feeding movement of the cloth. Just prior to the end of this forward 50 feeding movement, the shoulder 78 of the cam wheel 39 drops into the recess 63 to permit the free end of the feed bar 60 to be raised upwardly out of contact with the cloth by the spring 82. Just after this has taken place, the high point 81
- 55 of the cam 34 rides upwardly out of contact with the lever arm 75 and thus releases this lug, which is secured to the feed bar 60 so that the latter will be moved forwardly by the spring 82 to its original position. The parts are now in
- 60 position for a subsequent cycle of operations, for when the needle bar again descends it will take a forward stitch in the cloth and strike the piercer head to cause the latter to be moved downwardly, as previously explained.
- 65 It will be understood that in order to effect a complete hemstitching operation, it is necessary that the cloth be passed through the attachment twice. After passing through the machine once, as above described, it is turned end for end
- 70 and again put through the attachment. On this second travel of the cloth through the machine, it will be understood that as the cloth is put through in the opposite direction, the lateral stitches will be made on the side of the openings
- 75 opposite that upon which they were made during

the first travel of the cloth, thus completing the hemstitching operation.

In the form of my device which has heretofore been described, it will be recalled that while the piercer is first moved downwardly by engagement of the needle bar with the member or extension 47^a, subsequently the piercer is moved downwardly through the same opening in the cloth by one of the arms of the cam 31. In Figs. 18 and 19 of the drawings, I have shown a somewhat modified form of attachment wherein the piercer is operated entirely by the needle bar and moves upwardly and downwardly in synchronism with the movements of the needle bar. According to the modification shown in these figures of the drawings, the cam wheel 31 is replaced by the circular disk 31^a. This disk merely acts as a stop for the piercer arm 47^d to limit the upward movement of the latter. The notches 56 and 57 shown in the piercer arm in Fig. 7, for example, 20 may be, and preferably are, omitted in the arm 47^d shown in the modification in Figs. 18 and 19. The piercer arm is, however, provided with the extension 47^a which extends laterally into the path of the needle bar and is adapted to be engaged by the latter and moved downwardly through the cloth at each downward stroke of the needle bar. The spring 55 moves the arm 47^d upwardly when this movement is permitted by the upward movement of the needle bar, so 30 that according to this construction the piercer arm follows the movements of the needle bar. It will of course be understood that in this instance the piercer is not held downwardly in the opening in the cloth during the lateral movement of the cloth but is carried upwardly by the spring 55 after each downward stroke along with the needle bar, so that it is not engaged in the opening in the cloth when the latter is moved in a lateral direction. In other respects the 40 modification shown in Figs. 18 and 19 is similar to that shown in Figs. 1 to 14.

While we have shown and described a preferred embodiment of the invention, it will be understood that it is not to be limited to all of the 45 details shown, but is capable of modification and variation within the spirit of the invention and within the scope of the appended claims.

What we claim is:

1. A hemstitching attachment for sewing machines including a feed bar adapted to engage and move the work, said feed bar being provided with resilient work-engaging means, said means comprising a pair of resilient members secured to the bar at their rear ends only and projecting 50 forwardly therefrom.

2. A hemstitching attachment provided with a feed bar to impart a feeding movement to the work, said feed bar being provided adjacent one end with work-engaging means projecting forwardly of said bar, and said means being of resilient material and extending on opposite sides of the needle whereby the pressure upon the work upon opposite sides of the needle will be equalized.

3. A hemstitching attachment provided with a movable feed bar, and work-engaging means situated at one end of said bar, said means comprising a pair of laterally spaced spring fingers extending forwardly beyond the bar.

4. A hemstitching attachment provided with a movable feed bar, work-engaging means situated at one end of said bar, said means comprising a pair of laterally spaced spring fingers connected to the feed bar at their rear ends and extending forwardly from said bar, and friction 75

means on the under sides of said fingers to engage the work.

5. A hemstitching attachment provided with a movable feed bar, work-engaging means situated at one end of said bar, said means comprising a pair of laterally spaced spring fingers, and the under side of said bar being provided with work-engaging teeth rearwardly of said fingers.

10. A hemstitching attachment comprising a frame, a feed bar slidably connected with said frame, said slidable connection comprising a slot in one of said members and a headed pin in the other of said members, and said slot having an enlarged portion at one end thereof to permit the 15 passage of the head of said pin to provide for detachment of the bar from the frame, and means normally preventing said pin head from registering with the enlarged portion of said opening.

20. 7. A hemstitching attachment for sewing machines comprising a frame member adapted to be secured to the presser bar of the machine, means for feeding the cloth past said attachment comprising a feed bar movably attached to the 25 frame member and adapted for longitudinal and vertical movement, and means to move said feed bar longitudinally of the frame including a rotatable cam member carried by the frame, a lever pivoted on a horizontal axis for actuation by said cam member, and a part secured to the feed bar and in turn actuated by said lever.

30. 8. A hemstitching attachment for sewing machines comprising a frame member adapted to be secured to the presser bar of the machine, 35 means for feeding the cloth past said attachment comprising a feed bar movably attached to the frame member and adapted for longitudinal and vertical movement, and means to move said feed bar longitudinally of the frame including a rotatable cam member carried by the frame, a lever actuated by said cam member, and a part secured to the feed bar and in turn actuated by said lever, said lever having an adjustable pivot whereby the length of the feed step may be 40 adjusted.

45. 9. A hemstitching attachment for sewing machines comprising a frame member adapted to be secured to the presser bar of the machine, means for feeding the cloth past said attachment comprising a feed bar movably attached to the frame member and adapted for longitudinal and vertical movement, means to move said feed bar longitudinally of the frame including a rotatable cam member carried by the frame, 50 and an element pivoted on the frame on a horizontal axis, said element being actuated by said cam member and adapted to engage and move said feed bar.

55. 10. A hemstitching attachment for sewing machines comprising a frame member adapted to be secured to the presser bar of the machine, means for feeding the cloth past said attachment comprising a feed bar movably attached to the frame member and adapted for longitudinal and vertical movement, means to move said feed bar longitudinally of the frame including a rotatable cam member carried by the frame, an 60 element movably mounted on the frame actuated by said cam member and adapted to engage and move said feed bar, and means to adjust the throw of said element by said cam member.

65. 11. A hemstitching attachment for sewing machines comprising a frame member adapted to be secured to the presser bar of the machine, means for feeding the cloth past said attach- 70

ment comprising a feed bar movably attached to the frame member and adapted for longitudinal and vertical movement, means to move said feed bar longitudinally of the frame including a rotatable cam member carried by the frame, a bell 5 crank lever pivoted to the frame having one arm thereof in engagement with said cam member and another arm thereof in engagement with a part of said feed bar whereby the latter is actuated by the cam, and means to adjust the pivot of said lever to vary the length of the feed step.

12. A hemstitching attachment for sewing machines comprising a frame member adapted to be secured to the presser bar of the machine, 15 means for feeding the cloth past said attachment comprising a feed bar movably attached to the frame member and adapted for longitudinal and vertical movement, means to move said feed bar longitudinally of the frame including a rotatable cam member carried by the frame, a part 20 secured to said feed bar and actuated by said cam member, and means movable into position between said part and said cam member to vary the length of the feed step. 25

13. A hemstitching attachment for sewing machines comprising a frame member adapted to be secured to the presser bar of the machine, means for feeding the cloth past said attachment comprising a feed bar movably attached to the frame member and adapted for longitudinal and vertical movement, means to move said feed bar longitudinally of the frame including a rotatable cam member carried by the frame, a part 30 secured to said feed bar and actuated by said cam member, and a pivoted element swingable into and out of position between said part and said cam member to vary the movement of the feed bar by the cam member. 35

14. A hemstitching attachment for sewing machines comprising a frame member, a feed bar 40 slidably connected to said frame member for longitudinal movement, means to move said feed bar longitudinally of the frame comprising a cam rotatably mounted on the frame, a lug secured to the feed bar, a lever pivoted on the frame having one arm engaging said cam member and the other arm engaging said lug, and an element pivoted to said lug and movable into and out of position between the lever arm and said lug to vary the movement of the feed bar by 45 the cam member. 50

15. A hemstitching attachment comprising a frame member adapted to be attached to the presser bar of a sewing machine, means carried 55 by said frame to feed the material laterally and forwardly of the machine, a piercer member, and a carrier for said piercer member movably associated with the frame, said piercer member being movably secured to the carrier for movement to inoperative position. 60

16. A hemstitching attachment comprising a frame member adapted to be attached to the presser bar of a sewing machine, means carried 65 by said frame to feed the material laterally and forwardly of the machine, a piercer member, a carrier for said piercer member movably associated with the frame, said piercer member being movably secured to the carrier for movement to inoperative position, and a stop on the carrier to limit the resetting of said piercer member to its original position. 70

17. A hemstitching attachment comprising a frame member adapted to be attached to the presser bar of a sewing machine, means car- 75

ried by said frame to feed the material laterally and forwardly of the machine, an arm pivoted to the former member, a piercer head carried by said arm, and a piercer member carried by said head, said piercer head being pivotally secured to said arm to swing the piercer to inoperative position.

18. A hemstitching attachment comprising a frame member adapted to be attached to the presser bar of a sewing machine, means carried by said frame to feed the material laterally and forwardly of the machine, an arm pivoted to the former member, a piercer head carried by said arm, a piercer member carried by said head, said piercer head being pivotally secured to said arm to swing the piercer to inoperative position, and means on said arm engaging said head to limit the movement of the piercer when reset to its original position.

20. 19. A hemstitching attachment comprising a frame, operating mechanism on said frame for moving the cloth laterally and forwardly and for piercing openings in the cloth, said mechanism including a shaft rotatably mounted in the frame and actuated from the needle bar of the sewing machine, said shaft having an enlarged portion at one end thereof presenting a shoulder, a ratchet wheel non-rotatably secured upon said end, a hub member lodged against said shoulder, a key 30 upon said shoulder and said hub having a key way facing the shoulder in which the key is received.

20. A hemstitching attachment comprising a frame, a feed bar operatively connected to the frame for lateral and longitudinal movements relatively thereto, a piercer arm pivoted to the frame for vertical movement relatively thereto, and means connecting said piercer arm to said feed bar to positively move the former laterally with the latter in both directions, said means permitting vertical movement of the piercer arm independently of the feed bar.

21. A hemstitching attachment comprising a frame, a feed bar operatively connected to the frame for lateral and longitudinal movements relatively thereto, a piercer arm pivoted to the frame for vertical movement relatively thereto, and means connecting said piercer arm to said feed bar to move the former laterally with the latter in both directions, said means permitting vertical movement of the piercer arm independently of the feed bar, and said means comprising projections on said feed bar, one engaging each side of said piercer arm.

55. 22. A hemstitching attachment comprising a frame, a feed bar operatively connected to the frame for lateral and longitudinal movements relatively thereto, a piercer arm pivoted to the frame for vertical movement relatively thereto, and means connecting said piercer arm to said feed bar to move the former laterally with the latter in both directions, said means permitting vertical movement of the piercer arm independently of the feed bar and said means comprising a depending finger on said piercer arm, and a slot provided in said feed bar into which said finger extends.

23. An L-shaped piercer member for hemstitching devices comprising a horizontal supporting portion and a vertical operating portion having a pointed end, said portions being disposed at an obtuse angle one to the other, and the taper of the point of said piercer being less on one side than on the other.

24. A hemstitching device having a piercer member, means for mounting said piercer mem-

ber in said device at an angle slightly inclined to the vertical, said piercer member having a pointed end, and said point being eccentric to the axis of said piercer.

25. A hemstitching device having a piercer member, means for mounting said piercer member in said device at an angle slightly inclined to the vertical, said piercer member having a pointed end, and said point being nearer that side of said piercer making an acute angle with the horizontal than to the opposite side.

26. A hemstitching attachment adapted to be secured to the presser bar of a sewing machine, a throat plate adapted to cover the feeding dog of the sewing machine below said attachment, 15 said attachment having a piercer member, said throat plate having an opening for said piercer member and an opening for the sewing machine needle, and said plate being provided with a depression in its upper surface forwardly and at 20 one side of said needle opening.

27. A throat plate for use with a sewing machine hemstitching attachment having a piercer bar, said throat plate having a laterally elongated opening for the piercer, an L-shaped depression rearwardly of said opening, and a needle opening at the angle of said depression.

28. A throat plate for use with a sewing machine hemstitching attachment having a piercer bar, said throat plate having a laterally elongated opening for the piercer, a depression extending rearwardly from said opening, and a needle opening located in said depression.

29. A throat plate for use with a sewing machine hemstitching attachment having a piercer, 35 said throat plate having an opening to receive the piercer, said opening being elongated transversely of the direction of travel of goods through the machine, and indicating means on said throat plate intermediate the ends of, and adjacent the 40 edge of, said opening to mark the position of the piercer.

30. A hemstitching attachment for sewing machines comprising a frame adapted to be attached to the presser bar of the machine, an 45 arm hinged to the frame, a piercer carried by said arm, means attached to said arm and extending into the path of movement of the needle bar of the sewing machine whereby the descent of the needle bar strikes said means and 50 forces the piercer downwardly, spring means to cause said arm to follow the needle bar upon the upward stroke of the latter, and means having fixed position with respect to the path of movement of the arm to limit the upward movement thereof.

31. A hemstitching attachment for sewing machines having a presser bar and a needle bar, said attachment comprising a frame adapted to be attached to the presser bar, an arm pivoted to 60 said frame, a piercer secured to said arm, and means for effecting upward and downward movement of said arm in synchronism with the movement of the needle bar.

32. A hemstitching attachment for sewing machines having a needle bar and a presser bar, said attachment comprising a frame adapted to be attached to the presser bar, a piercer arm pivotally secured to the frame and carrying a piercer adjacent one end thereof, means secured to said 70 arm and extending in the path of the needle bar whereby the latter forces the piercer arm downwardly, means to raise the piercer arm upwardly after each stroke of the needle bar and means having fixed position with respect to the 75

path of movement of the arm to limit the upward movement thereof.

33. A hemstitching attachment for sewing machines comprising a frame, a presser foot carried by said frame, a piercing device movably mounted on the frame, said presser foot being provided with an opening to permit passage of the piercing device and sewing needle therethrough, and the portion of said opening adjacent the piercing device being enlarged laterally with respect to the remainder of said opening to permit lateral movement of the piercing device and provide support of the work by the edges of said opening closely adjacent said device.

15 34. A hemstitching attachment for sewing ma-

chines comprising a frame, a presser foot carried by said frame, a piercing device movably mounted upon said frame, said foot being provided with an opening elongated in the direction of the feeding movement of the material therethrough to permit passage through said opening of the piercing device and sewing needle, the forward portion of said opening being extended in a lateral direction whereby it is of greater width than the rear portion of said opening to permit relative lateral movement between the 10 presser foot and piercing device.

GEORGE L. HINMAN,
CLIFFORD J. WORD.
